P. F. KING.
PLIER WRENCH.
APPLICATION FILED FEB. 13, 1922.

1,438,442.

Patented Dec. 12, 1922.

UNITED STATES PATENT OFFICE.

PERCIVAL F. KING, OF SHREVEPORT, LOUISIANA.

PLIER WRENCH.

Application filed February 18, 1922. Serial No. 536,317.

To all whom it may concern:

Be it known that I, PERCIVAL F. KING, a citizen of Canada, residing at Shreveport, in the parish of Caddo and State of Louisiana, have invented certain new and useful Improvements in Plier Wrenches, of which the following is a specification.

My invention relates to certain new and useful improvements in plier wrenches and particularly has for its object to provide a wrench of this character of a simple and effective construction in which the parts are so designed as to present maximum strength with lightness of weight and to provide means whereby the wrench may be readily adjusted to different sized nuts.

Another object of the invention is to provide a wrench of this character in which the sliding jaw operates on a horn carried by the opposite jaw, the sliding jaw being provided with friction gripping surfaces to engage the horn when pressure is applied and assist in holding the sliding jaw in proper position.

The invention also resides in those novel features of construction, combination and arrangement of parts, all of which will be first fully described and then be specifically pointed out in the appended claims, reference being had to the accompanying drawings, in which:

Figure 1 is a perspective view of the invention.

Figure 2 is a detail side elevation of the same showing the operation of the friction lock or gripping surfaces.

Figure 3 is a view similar to Figure 2, parts being in section, showing how the head of the horn cooperates to release the gripping surfaces.

Figure 4 is a cross section on substantially the line 4-4 of Figure 3.

In the drawings in which like numerals of reference designate like parts in all of the Figures, 1 is the lower jaw which is bifurcated to form ears 3 between which the end 4 of one handle 12 is pivoted at 5. The jaw 1 has its front end tapered as indicated at 2, to correspond with the similarly formed end 8 of the upper jaw 6. The jaw 6 has a passage 7 through which a horn 16 that is rigidly secured in any desired way to the jaw 1, passes, the horn 16 having a head 17 to limit the upward movement of the jaw 6 and also to tilt that jaw to release the gripping surfaces, when desired.

The jaw 6 is also bifurcated to form ears 9 between which the end 11 of the other handle 13 is pivoted at 10. The handles 12 and 13 are crossed, the handle 13 being slotted to permit passage of a portion of the handle 12 and the two being pivoted together at 15. The passage 7 of the jaw 6 has parallel sides (see Figure 4) but its end surfaces lie in planes 19 and 20 making angles 18 with each other.

The surface at one end of the passage 7 lies at the top while that 19 at the other end lies at the bottom, the surfaces 20-20 being similarly opposed. The surfaces 20-20 lie in substantial parallel planes, the arrangement being such that, when pressure is applied to squeeze the handles 12-13, if a nut is imposed between the ends 2 and 8 of the jaws 1 and 6, the jaw 6 will be held in tight gripping contact with the horn 16 through the pressure engagement of the surfaces 19 with opposite edges of the horn (see Figure 2) and thus the jaw 6 will be held against slipping. When it is desired to release the jaw, it is only necessary to spread the handles 12 and 13 and in order to allow the easy return of the jaw 6 into contact with the jaw 1 or allow its easy movement toward the jaw 1, the handles 12 and 13 are opened wide until the head 17 is engaged by the top surface of the jaw 6. This causes the jaw 6 to be rocked or tilted from the position of Figure 2 to the position of Figure 3, thereby releasing the friction surfaces 19 from gripping engagement with the horn 16 and throwing the jaw to such an angle that the passage 7 between the points 18-18 will be enlarged (see Figure 3), whereby as the handles 12 and 13 are squeezed together, the jaw 6 will freely move toward the jaw 1 without "sticking" to or gripping the upwardly curved horn 16.

From the foregoing it will be observed that as the jaw 6 is forced back from gripping pressure between the points 2 and 8 the upward curved horn 16 creates a natural wall of resistance increasing friction grip, but when the jaw 6 is carried toward the head 17 by the spreading of the handles 10 (pressure is then applied from point 10) it naturally swings into a position to bring the surface 20-20 adjacent to the horn thus giving it easy travel; the head 17 adjusts the jaw 6 so as to make its return down the sloping face of the horn 16 easy as it advances toward the jaw 1. While I have de-

scribed the horn as securely attached to the jaw it is obvious that the horn 16 may be made in one piece with the jaw 1, in which event the head 17 would be made detachable.

5 From the foregoing description, taken in connection with the accompanying drawings, the complete construction, operation and advantages of the invention will be clear to those skilled in the art to which it 10 appertains.

What I claim is:

1. A plier wrench comprising a pair of crossed handles, jaws hinged to the ends of said handles, one of said jaws having a 15 rigidly attached horn, the other jaw having a passage through which said horn projects, said horn having a head inclined to the plane of the gripping surface of the jaw to which the horn is attached, said jaw having 20 the passage being provided with friction gripping surfaces for engaging the horn when the handles are squeezed together and adapted, when said handles are separated and said jaw is brought into engagement 25 with the head of the horn, to tilt the jaw and thereby disengage the friction surfaces from the horn for the purposes described.

2. In a plier wrench, a pair of crossed handles pivoted together, a pair of jaws 30 pivoted to the respective handle ends, one of said jaws having an upwardly curved horn terminating in a head inclined to the plane of the jaw which carries the horn, the second jaw having a passage through which 35 the horn projects, said passage having parallel side walls and having end walls lying in two sets of planes, whereby to provide upper and lower gripping surfaces adapted to be frictionally engaged with the 40 horn upon squeezing the handles together, said horn head adapted to tilt the moving jaw when the same is brought into engagement with the head and thereby release the friction gripping surfaces from the horn.

45 3. In a plier wrench, a pair of crossed handles pivoted together, a pair of jaws, one of said jaws being bifurcated and pivoted to the end of one handle and the other jaw being bifurcated and pivoted to the end of 50 the other handle, each of said jaws having tapering ends and opposing gripping faces, one of said jaws having an upwardly and

forwardly curved horn terminating in a head, the under surface of which lies in a plane inclined to the plane of the gripping 55 surface of the jaw which carries the horn, the other jaw having a passage and adapted to slide up and down on said horn, said other jaw being provided with upper and lower gripping surfaces in said passage for 60 frictionally engaging said horn in the operating position, said head, when engaged by the moving jaw, being adapted to tilt said moving jaw to release the gripping surfaces from said horn for the purposes specified. 65

4. A plier wrench comprising a pair of crossed handles, jaws hinged to the ends of said handles, one of said jaws having an upwardly curved horn, the other jaw having a passage through which said horn projects 70 said jaw having the passage being provided with friction gripping surfaces for engaging the horn when gripping pressure is applied between the points of the jaws opposite to their pivots, and means for tilting 75 the moving jaw when the handles are separated to release the moving jaw from gripping the horn for the purposes specified.

5. A plier wrench comprising a pair of crossed handles, jaws hinged to the ends of 80 said handles, one of said jaws having an upwardly projecting horn, the other jaw having a passage through which said horn projects, said jaw which has the passage being provided with gripping surfaces to engage the 85 horn when gripping pressure is applied between the points of the jaws opposite to their pivots, and means for tilting the moving jaw when the handles are separated to release the moving jaw from the gripping horn, for the 90 purposes specified.

6. A plier wrench comprising a pair of crossed handles, jaws hinged to the ends of said handles, one of said jaws having a horn, the other jaw having a passage through 95 which said horn projects with provisions for effecting a friction grip on the horn, when gripping pressure is applied, the hinged connection between said other jaw and its handle being a one way hinged connection, 100 whereby the handle connected with said other jaw will act as a one way lever to apply gripping pressure.

PERCIVAL F. KING.
